COIN LOCK

William B. Haskins and Hyman Schlosberg,
Los Angeles, Calif.

Application December 5, 1942, Serial No. 467,978

10 Claims. (Cl. 194—74)

This invention relates to coin-controlled locks.

The invention is applicable to various key operable closures, but is more particularly intended for use in connection with pay toilets, in which situation the improved construction which it provides is particularly valuable.

Among the objects of the invention are: to provide improved means for preventing the inserted coin from entering the receiving compartment provided therefor until it has fully performed its lock-controlling function; to provide improved means to indicate whether or not the toilet is in use; to assemble the coin-controlled locking elements in a more compact manner, and to reduce the number of operating parts required to perform the various required functions.

More specific objects are to provide an actuating mechanism for the locking bolt which will always be in an operative condition, both from outside and inside the toilet, from the time the coin has been inserted until the person entering the toilet has fully closed the door; to provide an "in" and "out" indicator which can be moved to the "out" position only by the operation of the inner knob to open the door, and to mount the operating parts upon the locking bolt thereby enlarging its functional capacities and at the same time carrying into effect the space-economizing and simplifying features already mentioned.

This invention relates to an improvement upon applicants' co-pending application Serial No. 423,778, filed December 20, 1941, which has matured into Patent No. 2,311,659, issued February 23, 1943.

Other objects, advantages and features of invention will hereinafter appear.

Referring to the accompanying drawing, which illustrates what is at present deemed to be a preferred embodiment of the invention,

Fig. 1 is a front elevation of the device showing the same applied to a toilet, showing a fragment of a swingable toilet door and of that part of the casing with which the free edge of said door cooperates.

Fig. 2 is a vertical section on line 2—2 of Fig. 1.

Fig. 3 is a vertical section on line 3—3 of Fig. 2, the scale being larger than that of the latter view and the lower portion of the lock casing being broken away to contract the view.

Fig. 4 is a horizontal section on line 4—4 of Fig. 3, parts shown in the right hand portion of the latter view being broken away.

Fig. 5 is a reproduction of Fig. 4 except that certain parts are shown in a different operative position.

Fig. 6 is a perspective view of the locking bolt looking upwardly thereat.

Fig. 7 is a section taken on line 7—7 of Fig. 6.

Referring in detail to the drawing, the combination lock and coin casing 10 is of an elongated rectangular character and is shown attached to the outer side of a swingable door 11 of a toilet with its longest dimension extending vertically. The casing mounting means shown includes a back plate 12 overlying the front face of said door and attached thereto by screws 13. Said plate 12 is furnished with internal ribs 14 which abut internally against the side and top walls of the casing to safeguard against unauthorized persons inserting a tool under the edges of said walls to pry the body portion of the casing away from its back wall 12 and thereby extract coins collected in said casing.

The front wall 20 of the casing, preferably made integral with its top and side walls, is provided with an inwardly directed bearing extension 21, into which screws, in a turnable manner, the threaded portion 22 of the shaft 23 of the inner knob 24, said knob and shaft being mounted in a conventional manner upon the door 11. Radially from said shaft extends a locking bolt retracting arm 25 which is fixed to the inner part of said threaded portion 22 of said shaft, and which acts upon the locking bolt.

The locking bolt 26 slidably fits within suitable apertures provided for it in the opposite side walls of the lock casing, said bolt having a beveled striking portion 27 which cooperates with the catch plate 28 mounted upon the door casing or jamb 29. Said bolt carries a backwardly projecting pin 30 which the aforesaid radial arm 25 engages to retract the bolt against the opposition of a compression spring 31 which acts between the casing wall and a shoulder 32 (see Fig. 3) with which the bolt is provided. The locking bolt carries a stop stud 26a which cooperates with the bearing portion 26b at that side of the casing from which the locking bolt is extensible.

Describing now the coin-controlled means whereby the door may be opened from the outside by means of the outer knob 35, this knob has a short shaft 36 which extends turnably through the front casing wall 20 and has fixed to it internally of the casing a swingable cross-head 37 which always extends in a generally vertical direction. Above the shaft 36 this cross-head at times engages a stop 38 which limits the swing thereof toward that side of the lock casing from which the striking part of the lock bolt projects, (hereinafter termed a right hand swing) and below the shaft 36 said cross-head has connected

to it a tension spring 39 which tends to swing the cross-head in the direction required to cause it to engage said stop 38 (hereinafter termed a left hand swing).

Ordinarily imparting swinging movement to the cross-head 37 will not materially affect the position of the locking bolt, but these parts are so constructed and related to each other that when a suitable coin is introduced into the casing through the coin chute 41 provided within the upper portion of the casing said coin will function as an abutment member between said cross-head and locking bolt to cause the operation of the exterior knob 35 to retract said bolt. For this purpose said bolt has a vertical coin slot 43 cut into it from its front side across the greater portion of its width and, to add width to this slot, an interiorly grooved or slotted extension 44 is welded or otherwise secured to the bolt at this point, the slot 45 of which alines with and extends the width of the locking bolt slot 43. The widened slot thus provided allows the coin to pass downwardly through the bolt except when the downward movement of the coin is obstructed from below by means of a coin arresting lip 46 carried by the aforesaid cross-head 37, which lip is positioned to support the coin with a portion of its lower part projecting below the locking bolt, an inserted coin always being thus supported until the locking bolt is retracted by the operation of the inner knob 24, or else by reason of engaging the catch plate 28 when the door is completely closed.

The cross-head 37 is provided behind and beyond its lip 46 with a narrowed coin-engaging extension 47 whereby the coin 50 is utilized as an abutment against which said extension acts to retract the locking bolt. An arcuate recess 53 is cut into a corner portion of the lower side of the locking bolt thereby providing, behind the attached extension 44, a clearance through which the swingable coin-engaging extension 47 may idly move when no coin is present to serve as an abutment to cause retraction of the locking bolt. By the construction which has just been described, not only the part of an inserted coin which projects below the body portion of the locking bolt is positioned to be acted upon by the member 47 to retract the locking bolt, but also a considerable part of the coin above its said projecting portion is maintained in the path of the bolt retracting member 47.

In the upper portion of the front wall 20 of the casing there is provided a sight opening 60 through which at all times may be seen the word "In" or else the word "Out," these words being inscribed upon an indicator plate 61 slidably underlying said wall. This indicator plate is mounted upon a U-shaped carriage 62 which slidably embraces the locking bolt with its limbs directed forwardly and its back part slotted at 63 to provide a clearance for the locking bolt stud 30, said back part also carrying a stop 64 which limits the swing of the lock bolt operating arm 25 when said arm returns from its bolt-retracting movement.

Said carriage 62 also carries an upwardly directed pin 65 which extends loosely through the mid-length portion of an angular dog 66 the nose of which at times engages a casing stud 67 to maintain the aforesaid indicator plate 61 in the "in" position, said dog being at times urged to this position by the action of a tension spring 68 one end of which is attached to the backwardly directed operating limb 69 of said dog

and the opposite end of which is attached to the coin chute 41. A compression spring 62x, located between the carriage 62 and the adjacent end wall of the casing, urges the carriage toward the free edge of the toilet door, this spring being aided by the spring 68 which causes said dog to engage the stud 67.

The lower limb of the U-shaped carriage 62 is located in the path of the final portion of the bolt-retracting swing of the coin-engaging member 47 which is operated by the outer knob 35, hence when a coin has been inserted and this knob is given a complete door-operating (right hand) turn the carriage 62 is moved by the action of the coin thereon against the opposition of its spring 68 to a position wherein the dog 66 passes over the stud 67 and then engages said stud to hold the carriage against return movement and in a position wherein the plate 61 displays the word "In" at the sight opening 60. A stop 37s is provided for the cross-head 37 to stop said head before it moves said carriage quite far enough to release the dog 66 unless its action on the carriage is augmented by the thickness of an inserted coin.

In order to provide for releasing the carriage from its retracted position the aforesaid backwardly directed limb 69 of the dog is extended back far enough to be engaged by the lock bolt operating arm 25 during the final part of its swing when the inner knob 24 is turned sufficiently to release the locking bolt. A desirable way to extend said dog limb 69 is to provide in it a screwthreaded socket to receive a screw pin 70 which serves the purpose of attaching the spring 68 to the dog as well as to extend said dog limb into the path of said arm 25. Said dog is pivoted to swing about a center spaced considerably back of the top of the stud 67, therefore when the dog is released its nose snaps back to a position wherein it overlies the top of said stud so that the dog will continue released as the free end portion of the lock bolt operating arm moves toward the free edge of the toilet door.

A key operable means is provided to enable authorized persons to open the toilet door without using a coin. For this purpose there is provided a conventional tubular lock structure 76 having an exterior key hole 77 at its front end and at its opposite end carrying a radially extending key operable arm 78 furnished with a pin 79 to engage, an upstanding arm 80 carried by the locking bolt near its beveled end.

The back plate 12 of the casing has an internally projecting boss 85 located at the mid-width and somewhat below the mid-height thereof and a key-controlled screw bolt 86 screws into this boss to aid in holding in place all parts of the casing except its back wall. This part of the structure includes a conventional lock barrel 87 having a keyhole 88. Also, the front casing wall has the internal boss or extension 21, already mentioned, from which it is necessary to unscrew the threaded shaft portion 22 before the two wall portions of the casing can be separated. When this separation has been effected, in order to avoid spilling the coins collected, the top portion of the detached part of the casing should be swung outwardly and downwardly before the lower portions of the casing are withdrawn from each other.

A brief recapitulation of the operation is as follows: Assuming the toilet door 11 to be in the closed, locked condition, the parts will at such time be in the positions shown in Figs. 1, 3 and

4, at which time the locking bolt is extended. Also the carriage 62 is in its right hand (Fig. 3) position and consequently the indicator plate 61 mounted on said carriage is positioned to display the word "Out" through the sight opening 60. At such time and previous to the insertion of a coin, turning of the outer knob 35 together with its shaft 36 will cause the upper portion of the cross-head 37 to move idly back and forth through coin passage of the locking bolt without operating said bolt and although the carriage 62 will be partially retracted by this movement of the cross-head the stop 31s will arrest the latter before it moves the carriage far enough to move the dog 66 carried thereby fully to its stop engaging position, hence under these circumstances the carriage will be returned by spring 62x to the "out" indicating position as soon as the person attempting to enter without inserting a coin releases his hold upon the outer knob 35. This is the case because a coin must be present in the coin passage of the locking bolt before the operation of the outer knob will either retract said bolt or move said carriage far enough to cause the horizontally swingable dog 66 to engage its stop stud 67.

When, however, the person desiring to enter inserts the proper coin into the coin chute 41 such coin will drop down into the coin passage 43 of the locking bolt in which position it will temporarily be supported by the coin-arresting lip 46 of the cross-head 37. With the coin present operating the knob 35 and thereby swinging of said cross-head leftward from the position shown in Fig. 3 will utilize the coin as an abutment whereby the locking bolt will be retracted and not later than the instant said bolt is unlocked will retract the carriage 62 far enough both to display the word "In" through the sight opening 60 and to cause the dog 66 to engage its stop and hold the carriage against retraction with the "in" signal in place so long as the toilet is occupied.

However, as soon as the outer knob 35 is released the cross-head 37 will be swung back to its original position by the spring 39 and the locking bolt will automatically move to the locked position so that its outer end will project from the casing 10, then, when the beveled surface 27 strikes against the striker plate on the door casing after the person has entered the toilet the bolt will be cammed back by such action releasing the coin from the slot 43 and permitting it to drop into the bottom of the casing.

When the occupant of the toilet leaves he will turn the inner knob 24 thereby swinging the arm 25 against the locking bolt stud 30, said arm 25 striking the pin 78 of the dog 66 and releasing the latter by the time the locking bolt has been withdrawn sufficiently to permit the door to be opened. Upon the removal of the operator's hand from the inner knob 24 the springs will operate to reset all parts to the original or normal position which includes moving the carriage and its indicating plate 61 to the "out" position.

Even if the door should not be completely closed by a person while using the toilet, it is to be understood that the door closing spring with which the toilet door is provided will completely close said door upon his departure, thus causing the catch plate automatically to retract the locking bolt and unseat the coin independent of the operation of any other mechanism.

It should be understood that the present disclosure is for the purpose of illustration only and

that this invention includes all modifications and equivalents which fall within the scope of the subject matter claimed.

What is claimed is:

- 5 1. In a coin controlled device for locking and unlocking toilet doors, a casing, means whereby said casing is supported upon the toilet door, a horizontally extending locking bolt mounted in said casing and having a locking end portion extensible therefrom, coin controlled means operable from the outer side of the toilet door to retract said locking bolt, a carriage within said casing slidably mounted upon said locking bolt, an indicator mounted upon said carriage, said indicator being observable from the exterior of said casing and in one position of said carriage indicating that the toilet is occupied and in another position thereof that the toilet is unoccupied, a dog supported on a pivot which is a part of said carriage, a stop on said casing engageable by said dog, the aforesaid retraction of the locking bolt after the insertion of a coin also moving said carriage and dog to a position wherein the latter engages said stop to hold said carriage against a return movement, said dog consisting of two arms angularly related to each other, one of said arms functioning as a pawl and the other as an arm for operating the pawl portion of the dog, said dog having a limited swinging movement during which its said operating arm at all times extends in a generally transverse direction in regard to the length of the locking bolt, a knob-carrying shaft having its bearings on said casing and operable from the inner side of the toilet door, an arm fixed to and extending radially from said shaft, said radial arm being positioned to retract the locking bolt and simultaneously engage the operating arm of said dog thus to retract said locking bolt and release said dog, and spring means which opposes the action of said radial arm upon said locking bolt and dog and which upon the release of the latter restores said carriage indicator carried thereby and locking bolt to their original positions when the operator removes torsional force from the knob whereby the aforesaid shaft is operated.
- 10 2. The subject matter of claim 1 and, there being a single spring acting between said dog and the casing whereby said carriage is retracted and said dog is urged toward its stop-engaging position.
- 15 3. The subject matter of claim 1 and, there being a single tension spring whereby said carriage is retracted and said dog is urged toward its stop-engaging position, one end of said spring being attached to the operating arm of said dog and the other end of said spring being attached to the casing.
- 20 4. In a locking device, a casing mountable on a toilet door, a locking bolt mounted in said casing to slide horizontally to and from the locking position, a carriage mounted upon said locking bolt and slidably longitudinally thereof, an indicator carried by said carriage to indicate whether or not the toilet is occupied, a spring within said casing tending to move said carriage to one limit of its travel in which position said indicator indicates that the toilet is unoccupied, coin controlled means within the casing and manually operable from the exterior of the toilet simultaneously to retract said locking bolt and move said carriage against the opposition of said spring to a position wherein said indicator indicates an occupied toilet, a vertical pin fixed to said carriage, a dog swingably mounted on said pin, a stop fixed to
- 25
- 30
- 35
- 40
- 45
- 50
- 55
- 60
- 65

- 75

the casing and engageable by the portion of said dog at one side of said pin to releasably maintain said carriage in the latter position, at the opposite side of said pin said dog being connected to said spring to be thereby releasably maintained in engagement with said stop when said carriage is moved as aforesaid to the position wherein an occupied toilet is indicated, and means mounted upon said casing and manually operable from the interior of the toilet to retract said locking bolt and release said dog.

5. The subject matter of claim 4 and, said dog having an operating arm which projects toward the interior of the toilet, and means operable from the interior of the toilet including a part engageable with said operating arm of the dog to release the latter.

6. In a locking device, a casing mountable on a toilet door, a locking bolt mounted in said casing to slide horizontally to and from the locking position, a carriage mounted upon said locking bolt and slidably longitudinally thereof, an indicator carried by said carriage to indicate whether or not the toilet is occupied, a spring within said casing tending to move said carriage to one limit of its travel in which position said indicator indicates that the toilet is unoccupied, coin controlled means within the casing and manually operable from the exterior of the toilet simultaneously to retract said locking bolt and move said carriage against the opposition of said spring to a position wherein said indicator indicates an occupied toilet, a stop carried by the casing, a dog mounted upon said carriage and engageable with said stop to releasably maintain said carriage and indicator in the position wherein an occupied toilet is indicated, there also being a stop carried by the casing which arrests the movement of the aforesaid carriage moving means slightly before said dog becomes engageable with said stop when the coin is absent, the coin when present occupying a position intermediate said carriage and the aforesaid means for moving it, thus augmenting the movement imparted to said carriage by the last recited means and causing said dog to engage the aforesaid stop therefor.

7. The subject matter of claim 6 and, means mounted on said casing and manually operable from the interior of the toilet simultaneously to retract said locking bolt and release said dog from the aforesaid stop provided therefor.

8. In a locking device, a casing mountable on a toilet door, a locking bolt mounted in said casing to slide horizontally to and from the locking position, a carriage mounted upon said locking bolt and slidably longitudinally thereof, an indicator carried by said carriage to indicate whether or not the toilet is occupied, a spring within said casing tending to move said carriage to one limit of its travel in which position said indicator indicates that the toilet is unoccupied, coin controlled

means within the casing and manually operable from the exterior of the toilet simultaneously to retract said locking bolt and move said carriage against the opposition of said spring to a

5 position wherein said indicator indicates an occupied toilet, a dog mounted upon said carriage, a stop on said casing and engageable by said dog releasably to maintain said carriage in the position wherein the aforesaid indicator carried 10 thereby indicates an occupied toilet, there being also a stop carried by the casing which arrests the movement of said carriage moving means slightly before said dog becomes engageable with said stop when the coin is absent, the coin when 15 present being supported by the aforesaid carriage moving means in a position wherein it forms an abutment which augments the action of the latter upon said carriage and causes the latter to move far enough to bring its dog into engagement with 20 the stop therefor, the inserted coin also forming an abutment whereon said carriage moving means acts to retract the locking bolt independently of said carriage when the latter is retained in the occupied indicating position, and means mounted 25 upon the casing and manually operable from within the toilet simultaneously to retract the locking bolt, release said dog, and move an inserted coin away from its aforesaid support to permit it to gravitate to a lower position of the casing.

9. The subject matter of claim 8 and, the inserted coin, prior to its aforesaid release, occupying a passage provided therefor in the locking bolt.

35 10. In a locking device, a casing mountable on a toilet door, a locking bolt mounted in said casing to slide horizontally to and from the locking position, a carriage mounted upon said locking bolt and slidably longitudinally thereof, an indicator carried by said carriage to indicate whether or not the toilet is occupied, a spring within said casing tending to move said carriage to one limit of its travel in which position said indicator indicates that the toilet is unoccupied, coin controlled 40 means within the casing and manually operable from the exterior of the toilet simultaneously to retract said locking bolt and move said carriage against the opposition of said spring to a position wherein said indicator indicates an occupied toilet, a dog mounted within the casing to releasably maintain said carriage in the latter position, and means manually operable from the interior of the toilet to retract said bolt and release said dog, said dog being mounted upon said carriage 45 and said spring being connected to said dog to move the latter toward its carriage retaining position whenever said carriage is moved to the limit of its movement against the opposition of said spring.
